[57] CLAIM

The ornamental design for a reflector, as shown and described.

DESCRIPTION

FIG. 1 is a side elevational view of a reflector showing my new design;

FIG. 2 is an elevational view of the side opposite FIG. 1;

FIG. 3 is a fragmentary view looking from the top of FIG. 1;

FIG. 4 is an enlarged fragmentary front perspective view;

FIG. 5 is an enlarged rear elevational view of FIG. 4 with the support shaft omitted for convenience and clarity of illustration.

The broken line portion of a bicycle wheel shown in FIG. 1 is for illustrative purposes only.
